(No Model.)

M. HORWITZ.
BURNER FOR INCANDESCENT GAS LIGHTING.

No. 530,775.

Patented Dec. 11, 1894.

UNITED STATES PATENT OFFICE.

MORITZ HORWITZ, OF BERLIN, GERMANY.

BURNER FOR INCANDESCENT GAS-LIGHTING.

SPECIFICATION forming part of Letters Patent No. 530,775, dated December 11, 1894.

Application filed June 22, 1894. Serial No. 515,348. (No model.)

To all whom it may concern:

Be it known that I, MORITZ HORWITZ, a subject of the Emperor of Germany, residing at Berlin, Germany, have invented certain 5 new and useful Improvements in Burners for Incandescent Gas-Lighting, of which the following is a specification.

My invention has relation to that class of gas lamps in which the full illuminating effect is produced by the incandescence of a mantle, hood or body suspended about or above the burner; and in such connection it relates more particularly to the construction and arrangement of such a burner for said 15 purpose.

The principal objects of my invention are first, to provide a burner arranged somewhat on the plan or type of a Bunsen burner for lighting purposes by employing an incandescent mantle or body suspended therefrom in a certain manner; second, to provide a burner arranged in such manner as that without the aid of mechanical devices or appliances the flame is made to spread or diffuse the light 25 so that every part of the incandescent mantle or body is brought into contact with the flame, whereby said mantle or body is thoroughly utilized and a maximum illumination is derived therefrom; and third, to provide a 30 burner in which the spread or diffusion of the flame is effected by means of a strong current of air conveyed through the center of the flame, whereby the air spreads the flame outwardly into tubular form and causes the same to contact with a truncated incandescent mantle or body so that every part of the latter is made to glow.

My invention consists of an incandescent gaslighting burner constructed, arranged and 40 adapted for operation in substantially the manner hereinafter described and claimed.

The nature and scope of my invention will be more fully understood from the following description taken in connection with the accompanying drawings forming part hereof; and in which—

Figure 1, is a vertical section through a burner embodying features of my invention. Fig. 2, is a similar view of a modified form 50 thereof. Fig. 3, is a similar view of a still further modified form of said burner. Fig. 4, is a view partly in plan and partly in hori-

zontal section of a disk provided with a double row of perforations of the burner of Fig. 3; and Fig. 5, is a top or plan view of a perforated plate of the burner taken on the line A—B, of Fig. 3.

Referring to the drawings with reference to Fig. 1, the burner consists of a casing *a*, to which is secured a conical throat *b*. *c*, is the gas inlet conduit, tube or duct formed preferably integral with or secured to the throat *b*, and provided with a series of oblong openings *c'*, through which openings air is led or drawn to permit of an admixture of the air and gas in the inlet conduit or tube *c*. In the casing *a*, a tube or shell *d*, is provided preferably in conical form, and having branches *e*, extending through openings provided in the conical throat *b*, to permit of the flow of pure air therethrough into the body of the tube or shell *d*. The object of such flow of the current of air into said internal shell *d*, is to effect a tubular like spreading or diffusing of the flame of the burner. The upper end of the tube or shell *d*, as illustrated in Fig. 1, is bent over to form a flange *f*, and the space between this flange and the casing *a*, forms an outlet for the gas held as it were by reason of said flange in suspension and in such manner as to avoid any unpleasant roaring of the flame. The current of air while the gas is burning, passes in the direction of the arrow in Fig. 1, out of the upper end of the shell *d*, and impinging against the flame, which consequently diffuses the same somewhat in tubular form and the incandescent body or mantle *x*, is thus acted upon by the flame at every point or portion thereof. This incandescent mantle *x*, of the form of a truncated cone, as fully illustrated in Fig. 2, is formed of thin interlaced threads of refractory material and is supported to position by means of a perforated disk *i*, connected with a pin or stem *g*, and which stem or pin at the lower end is provided with a perforated disk *h*, through which perforations the pure air passes vertically into the internal space around or about the body of the mantle *x*. The disk *h*, is preferably arranged so as to engage in the mouth in the upper portion of the conical shell or casing *d*, as illustrated in Fig. 1.

In the burner illustrated in Fig. 2, the mix-

ture of gas and air is conveyed through an annulus or ring c^2 , from the perforated inlet nozzle c^4 , into the chamber formed by the walls of the tubes or shells a' and d' , and the air enters through the open lower end of the inner tube d' , as indicated by the arrow in Fig. 2, and is forced or drawn against the inner surface of the flame. The space between the flange f' , of the tube d' , and the casing a' , forms a passage-way for the escape of the combustible mixture composed of air and gas. The perforated bottom plate f^2 , of the flange f' , serves to support a corresponding perforated plate h' , connected with the lower end of the pin or stem g , and carrying at its upper end a perforated disk i , preferably made of asbestos, mica or other suitable material, with which the incandescent mantle or body x , is engaged, to support the same to position within the chimney or globe z . The length of the stem and the diameter of the casing a' , are such as that the lower end of the incandescent body or mantle x , suspended from the disk i , snugly engages or contacts with the exterior surface of the casing a' . By this arrangement the flame is forced outward by the inner current of pure air, assuming the form of the incandescent body or mantle x , so that the latter is brought to a glow at every portion thereof. By turning the perforated disk h' , on its corresponding side or disk f^2 , in such manner as that the openings are more or less covered, the current of air can be readily regulated through the chamber or tube d' , as clearly illustrated in Fig. 2.

In Fig. 3, a still further modification of my invention is shown, and in which the combustible mixture of air and gas is conveyed through a divided or bifurcated pipe or conduit c^3 , from the perforated inlet nozzle or nipple c^4 . h , is a plate engaging the upper end of the forked or branch pipe or conduit c^3 , and having openings m and m' , communicating with the branches of the conduit c^3 , and a central opening n , leading to the central funnel shaped tube d^2 . The air is adapted to cause the flame to spread or diffuse through the pipe d^2 , in the direction of the arrow in Fig. 3. The casing a^2 , is suitably secured to the top edge of the disk or plate h . l , is a collar or open tapering hood engaging with said plate and extending upward concentrically or substantially so to the central conical tube d^2 . The object of this hood or collar l , is to confine to some extent the mixture of air and gas and thus secure the most thorough commingling of both constituents of the inflaming or gaseous mixture for insuring the best results in the burning thereof for illuminating purposes. The chamber between the casing a^2 , and the chamber d^2 , is closed at its upper end by means of a disk o . This disk is made of lardite or other suitable material and is provided with two series of openings o' , which taper toward their lower ends so as to form a circular opening o^2 , underneath the disk o . By means of this arrangement and the coni-

cal form of the tube d^2 , the combustible mixture is forced through the openings o' , under considerable pressure. The plate h^2 , of the stem g , is secured to the upper end of the tube d^2 , and is preferably provided with slanting openings and at its lower extremity with a conical projection h^3 , for directing the pure air in its passage through the tube d^2 , against the inner side or surface of the flame. An annular spring clamp or other suitable device for engaging the globe or shade z , at the lower end is secured to the casing of the lamp, in any well understood manner for holding the same to required position.

Having thus described the nature and objects of my invention, what I claim as new, and desire to secure by Letters Patent, is—

1. An incandescent gas burner, comprising a casing provided with a tapering bottom with a perforated nipple or nozzle, an internal tapering tube provided with branches for the introduction of air therethrough and with a flanged top arranged close to said casing so as to form a narrow passage between said tube and shell to permit of a thorough admixture of the air and gas, a stem provided with top and bottom disks, a mantle supported within a globe or shade from one of said disks and engaging said casing, substantially as and for the purposes set forth. 85

2. An incandescent gas burner, comprising a shell provided with a gas inlet communicating with a tubular chamber, a central air inlet formed therewith and provided with a flange forming a passage between the wall of said gas chamber and said air chamber, a perforated disk mounted in the upper end of said chamber, a stem provided at the upper end with a perforated disk, a mantle suspended therefrom and engaging the wall of said gas chamber and a globe or shade adapted to engage spring clamps of the casing of said lamp, substantially as and for the purposes set forth. 100

3. An incandescent gas burner, comprising a casing provided with spring clamps having a globe or shade detachably engaging therewith, a perforated inlet nipple or nozzle engaging a bifurcated and truncated shell having an open hood reversely tapering with respect to said shell, a tapering air chamber carrying a perforated disk with a tapering projection, a perforated plate mounted on said disk and provided with a stem supporting a 115 mantle composed of refractory material to required position, substantially as and for the purposes set forth.

4. An incandescent gas burner provided with a spring clamp having a shade or globe 125 in detachable engagement therewith, a tubular gas chamber provided with a contracted throat with a perforated inlet nipple or nozzle, a tapering air chamber having the upper end provided with a flange and with branches 130 in the lower portion thereof extending through the throat of said gas chamber, a stem provided with perforated disks at the upper and lower ends thereof, and a mantle suspended

from one of said disks and normally engaging the wall of said gas chamber, substantially as and for the purposes set forth.

5. An incandescent gas burner, comprising an inlet in communication with a chamber having a central air conduit with a flange, a perforated disk mounted in the upper end of said tube and provided with a stem or pin provided at the upper end with a perforated disk, a mantle supported therefrom and en-

gaging the wall of said chamber, and a globe or shade clamped to the casing of the burner, substantially as and for the purposes set forth.

In witness whereof I have hereunto signed my name in the presence of two subscribing ¹⁵ witnesses.

MORITZ HORWITZ.
